US00D901013S

(12) **United States Design Patent** (10) Patent No.: **US D901,013 S**
 Davies et al. (45) Date of Patent: ** Nov. 3, 2020

(54) **POROUS IMPLANT**

(71) Applicant: **ORTHO DEVELOPMENT CORPORATION**, Draper, UT (US)
 (72) Inventors: **Bryan K Davies**, Taylorsville, UT (US); **Alfred Despres**, Heber City, UT (US); **Susanne F Sealy**, Draper, UT (US)

(73) Assignee: **Ortho Development Corporation**, Draper, UT (US)(**) Term: **15 Years**(21) Appl. No.: **29/701,487**(22) Filed: **Aug. 12, 2019**(51) LOC (12) Cl. **24-03**
 (52) U.S. Cl. ..... **D24/155**(58) **Field of Classification Search**USPC **D24/155**
 CPC A61F 2/3859; A61F 2/38; A61F 2/389;
 A61F 2/3886; A61F 2/60; A61F 2/06;
 A61F 2/66; A61F 2/76; A61F 2310/00023

Primary Examiner — Charles D Hanson(74) *Attorney, Agent, or Firm* — Pate Peterson PLLC; Brett Peterson(57) **CLAIM**

We claim the ornamental design for a porous implant, as shown and described.

DESCRIPTION

FIG. 1 is a perspective view of a porous implant, showing our new design;

FIG. 2 is a top view of the porous implant.

FIG. 3 is a bottom view of the porous implant.

FIG. 4 is a left side view of the porous implant.

FIG. 5 is a right side view of the porous implant.

FIG. 6 is a front view of the porous implant; and,

FIG. 7 is a back view of the porous implant.
